(57) **CLAIM**

The ornamental design for a knurled flashlight grip, as shown and described.

DESCRIPTION

FIG. 1 is a front perspective view of the knurled flashlight grip;

FIG. 2 is a rear perspective view of the knurled flashlight grip;

FIG. 3 is a top view of the knurled flashlight grip;

FIG. 4 is a side end view of the knurled flashlight grip, the opposite side end view being a mirror image thereof; and,

FIG. 5 is a bottom view of the knurled flashlight grip. The broken lines are shown for illustrative purposes and form no part of the claimed design.
